(57) **CLAIM**

The ornamental design for a self-assembly platform bed, as shown and described.

DESCRIPTION

FIG. 1 is a perspective top view of an embodiment of a self-assembly platform bed of the present invention;

FIG. 2 is a side view, left or right, of the self-assembly platform bed of FIG. 1;

FIG. 3 is a top view of the self-assembly platform bed of FIG. 1;

FIG. 4 is a bottom view of the self-assembly platform bed of FIG. 1;

FIG. 5 is an end elevational view, front or back, of the self-assembly platform bed of FIG. 1;

FIG. 6 is a perspective bottom view of the self-assembly platform bed of FIG. 1; and,

FIG. 7 is a perspective top view of an alternate embodiment of a self-assembly platform bed of the present invention.

The broken lines are for environmental purposes only and form no part of the claimed design.
